UNITED STATES PATENT OFFICE.

ALEXANDER L. GEISLER, OF BRISTOL, RHODE ISLAND.

LOCKING HOOK.

Specification of Letters Patent. Patented Sept. 20, 1921.

1,391,625.

Application filed January 25, 1921. Serial No. 439,780.

To all whom it may concern:

Be it known that I, ALEXANDER L. GEISLER, a citizen of the United States, and a resident of Bristol, in the county of Bristol and State of Rhode Island, have invented a new and Improved Locking Hook, of which the following is a full, clear, and exact description.

This invention relates to improvements in locking hooks.

An object of this invention is to provide a device of this character which may function either as a key ring, a coupling link, or a hanger. When the device is constructed 15 in a suitable size to form a key ring, it will prove amusing as a puzzle for children.

A further object is to provide a locking hook which will be simple and practical in construction, efficient and durable in use, 20 and comparatively inexpensive to manufacture.

With these and other objects in view, the invention consists in certain novel features of construction and combinations and arrangements of parts as will be more fully 25 hereinafter described and pointed out in the claims.

In the accompanying drawings:

Figure 1 is a view in side elevation showing 30 my improved device in closed position in use as a key ring.

Fig. 2 is an edge view of Fig. 1 showing the device in open position.

Fig. 3 is a view in side elevation showing 35 the position of the parts when the device functions as a hanger.

Referring in detail to the drawings, 1 represents a spring loop formed by bending a single piece of spring metal. The metal 40 may be of any suitable thickness and any desired cross sectional shape, although it is preferably rectangular in cross section. The intermediate portion of the metal strip is bent to form the spring loop 1, and the ends 45 of the strip then extend in a parallel direction, the shorter end 2 being held against the longer end 3 by the spring action of the loop 1. The shorter end of the metal strip 50 is preferably tapered as indicated at 2'. The longer end 3 of the strip terminates in a substantially U-shaped hook 4 and the free extremity 5 of the hook extends back toward the loop 1. The tapered extremity of the end 2 is located within the hook and presses 55 against the end 3 as before noted.

By springing the end 2 to one side as

indicated in Fig. 2, a key such as 6 may be introduced onto the loop. A conventional form of nut such as 7 is then passed over the hook and on to the straight portion of the 60 end 3. The end 2 is then forced back into the position shown in Fig. 1 and the nut 7 is locked in position encircling the ends 2 and 3. It is to be noticed that the nut 7 is of a size which will permit ready slipping 65 on and off over the hook 4 when the end 2 is swung out of the way, but when the end 2 is in its normal position, it effectively prevents the application or withdrawal of the 70 nut.

The space between the body portion of the end 3 and its parallel extremity 5 is sufficient to permit the nut 10 to slip freely on and off of the hook, but when the shorter end or tongue 2 is located between the extremity 5 and the end 3, there is not sufficient intervening space between the extremity 5 and the tongue 2 to permit the nut to be turned and slipped off of the hook. 75

The nut 7 may be formed with an integral 80 apertured lug 8 receiving one end of a supporting chain such as 9.

In Fig. 3 I illustrate the device in use as a hanger suspended from the loop 1 by a shaft or rod 10, the hook 7 functioning to 85 support a depending member such as 11. When designed for this use, the device may of course be made of a size proportionate to the weight which it is to support.

It will be apparent that children will find 90 amusement endeavoring to remove or replace the nut 7 when the device is made in small sizes so that it may be manually operated.

Various slight changes and alterations 95 might be made in the general form and arrangement of the parts described without departing from the invention, and hence I do not limit myself to the precise details set forth but consider myself at liberty to make such changes and alterations as fairly fall 100 within the spirit and scope of the appended claims.

Having thus described my invention, what I claim as new and desire to secure by Letters Patent is:

1. A device of the character stated, comprising a strip of metal bent to form a spring loop, the ends of said strip being held against one another by the resiliency of the loop, an annular locking member adapted to encircle the two ends of the strip, one of said ends adapted to be sprung laterally to per-

- mit the introduction or removal of the locking member, and means preventing the introduction or removal of the locking member when said end is not sprung laterally.
- 5 2. A device of the character stated, comprising a single strip of metal having its intermediate portion bent to form a spring loop, and having its ends extending in parallelism and held against each other by the action of the loop, one of said ends being longer than the other end and terminating in a U-shaped hook, the free extremity of said hook extending back toward the loop, said shorter end adapted to be sprung to one side to permit the introduction of an article on to the loop, means for locking such an article on the loop, said means comprising an annular locking member encircling the parallel portions of the two ends,
- 10 15 10 15 20 3. A device of the character stated, com-

prising a single strip of metal having its intermediate portion bent to form a spring loop, and having its ends extending in parallelism and held against each other by the action of the loop, one of said ends being longer than the other end and terminating in a U-shaped hook, the free extremity of said hook extending back toward the loop, said shorter end adapted to be sprung to one side to permit the introduction of an article on to the loop, means for locking such an article on the loop, said means comprising an annular locking member encircling the parallel portions of the two ends, said locking member movable freely over the hook when the shorter end of the strip is sprung to one side, and locked against movement on the hook when the shorter end is in operative position.

ALEXANDER L. GEISLER.
